UNITED STATES PATENT OFFICE.

EDWARD N. CUMMINGS, OF LYNN, MASSACHUSETTS.

PIANISSIMO-ACTION FOR PIANOS.

SPECIFICATION forming part of Letters Patent No. 430,002, dated June 10, 1890.

Application filed July 10, 1889. Serial No. 317,045. (No model.)

To all whom it may concern:

Be it known that I, EDWARD N. CUMMINGS, a citizen of the United States, residing at Lynn, in the county of Essex and Commonwealth of Massachusetts, have invented certain new and useful Improvements in Upright Piano-Fortes, of which the following is a full specification.

Referring to the accompanying drawings, Figure 1 is an elevation, partly in section, of the piano-action and adjacent parts in position for playing at normal tone. Fig. 2 shows in plan the operation of the movable key-rest. Fig. 3 shows the same in elevation, the parts being there shown in position for playing at soft pedal. Fig. 4 is a plan view of a portion of the key-rest.

My invention consists of the hereinafter-described improvements in piano-fortes, where-
20 by the dip and touch of the keys remain the same whether playing the piano at its normal tone or at soft-pedal, the construction and arrangement being such that the movable bearing parts of the action are always in contact whatever be the position of the pedal-rod. Moreover, the sound of the piano may be graded beyond the soft-pedal, so as to be rendered partially, or, if desired, wholly, in-
25 audible while playing or practicing, at the same time keeping the dip and touch of the keys constant.

B is the key-bottom, from which arise stand-
ards A, supporting the working parts of the action, as shown in Fig. 1.

35 F is the key-rest hinged at I to the key-
bottom and normally resting thereon, and to this is secured the front rail G³, the balance-
rail F³, and the rear rail G², supporting the key-cloth G'.

40 G is the key fulcrumed on the balance-rail. I preferably use no rocker on the rear of the key for the lower end of the lifter M to bear against, but let the action-cloth g rest directly on the key itself, as shown in Fig. 1, while the 45 lifter M bears directly on the action-cloth. By means of the regulating-screws g' in the top of the key under the action-cloth the said cloth may be pressed upward and close contact with the lifter assured.

50 The lifter M, swing m pivoted thereto and to the lower rail A², jack-rocker R, and jack S are constructed and arranged in the usual

manner to operate the hammer K through the hammer-butt k and hammer-shank K'. The action of the damper L and damper-lever L' 55 is substantially the same as that ordinarily found in this class of pianos, and so needs no further description.

C is the pedal-rod, on the top of which rests the shoulder k² of the hammer-rail K², the 60 sides K³ of which are pivoted to the stand-
ards, the arrangement being such that as the
pedal-rod is raised from the normal position
shown in Fig. 1 the throw of the hammer is
decreased, thereby reducing the sound pro- 65

duced.

In upright pianos as ordinarily constructed, when, by the raising of the pedal-rod C the throw of the hammer is diminished and the sound reduced, the back-stop Q, which rises 70 with the hammer, lifts the jack-rocker R, through the influence of the bridle-tape q, and thus raises the lifter M from contact with the action-cloth. At the same time a space is left between the upper end of the jack and 75 the notch in the hammer-butt k, so that when the piano is played in this position it either has not the same dip and touch or there is much looseness of action due to the considerable space the key must be moved through in 80 bringing the parts again in contact before any effect whatever is produced on the ham-
mer K. It becomes necessary, therefore, to provide means for keeping the bearing parts of the action always in contact, and thus 85 keep the dip and touch of the key always the same whether the pedal-rod is up or down.

I accomplish this by a key-rest or key-frame F, hinged at its outer end at I to the key-bot-
tom, and whose inner end is raised or low- 90 ered by the pedal-rod. This key-rest F is
preferably made of metal—such as malleable
cast-iron—being a skeleton frame, as shown
in Fig. 4, provided with lugs f² F², whereby
the pieces G³, F³, and G² may be bolted or 95
screwed thereto. At the inner end of the
key-bottom B is bolted or otherwise secured
the piece E', made, preferably, of metal, and
supporting at intervals along its top the bear- 100
ings E², preferably cast with the piece E', in
which turns the rod E. Each end bearing E²
is provided with a cover E³, whereby the rod
E is held in place. This rod E turns freely
in its bearings and is jointed loosely in any

desired manner to the inner end of the key-rest F in such a way as to raise or lower the said inner end of the key-rest when the rod turns. I have here shown the rod provided at intervals with lugs e, having grooves in the outer ends thereof, in which grooves rest the heads of the screws f, held in flanges F' in the frame F at proper intervals to engage with the lugs e, the construction being clearly shown in Figs. 1, 2, and 3.

The pedal-rod C is provided with a sleeve C', screwed or otherwise secured thereto, to which sleeve is pivoted one end of an arm C², the other end of which is firmly secured to the end of the rod E in such a manner that when the pedal-rod is raised for the purpose of decreasing the throw of the hammer, as previously explained, the rod E turns in its bearings and raises the inner end of the key-rest F, so as to keep the action-cloth g always in contact with the end of the lifter and all the other bearing parts of the action in contact whatever the position of the pedal rod.

The sleeve C' is provided with a projection c, engaging with the end of a stop H, sliding, preferably, in the key-block H' at one end of the key-board and operated by the knob h, the shank of which moves in a suitably-slotted guide h'. The position of the projection c is such that with the stop in the position shown in Fig. 3 the said projection will engage with the inner end of the stop when the piano is to be played at soft pedal. The parts are shown in Fig. 1 in position for playing at the normal tone, in which case the key-rest F rests upon the key-bottom. In Fig. 3 I have shown the parts in position for playing at soft pedal, the inner end of the key-frame being in this case raised slightly, as shown, for the reasons explained. In Figs. 2 and 3 the working parts of the action are not shown. When it is desired to further reduce the sound beyond the ordinary soft pedal, the stop H is withdrawn beyond the range of the projection c and the pedal-rod raised farther, the effect being to still further lessen the throw of the hammer, while still keeping the bearing parts in contact, and hence retaining the dip and touch of the key constant. The sound may be reduced to nothing, if desired, in this way, and fingering of the keys may be practiced noiselessly. The under side of the projection c may be graduated in steps to engage with the inner end of the stop H at any desired position of the pedal-rod, so that the parts may be held in any position without keeping the foot upon the pedal. Moreover, by withdrawing the stop H and operating the pedal the sound of the piano may be very delicately graded in playing from the

normal tone to a mere nothing, while keeping the touch of the keys the same. Although by this arrangement the whole key-board in reality moves when the pedal is operated, yet the motion is imperceptible to the player, since the key-rest is hinged at its extreme outer end to the key-bottom, so that while the motion of the inner end of the keys is sufficient to fulfill its purpose that at the outer end where the fingering is done is practically nothing.

In adapting the parts of an upright-piano action to be played in this manner with all positions of the pedal-rod it has hitherto been a matter of difficulty to so shape the back-check as to engage with the face of the back-stop perfectly whatever the position of parts. If so shaped as to properly engage therewith at normal tone, it would not ordinarily strike squarely against it as soft pedal or especially when the pedal was raised far above this point.

In my improved piano I employ a back-check P, the face of which is perfectly straight and in one plane instead of having a curved face or two or more faces inclined, as ordinarily. This always strikes squarely against the flat face of the back-stop Q when playing with the parts in any position.

I claim—

1. A piano provided with a movable hinged key-rest, substantially as and for the purposes described.

2. A piano provided with a key-rest pivoted at its outer end, substantially as and for the purposes described.

3. The combination, with the action of a piano, of a pedal-operated movable hinged key-rest whereby the bearing parts of the action may be kept always in contact, substantially as described.

4. A piano provided with an open-metal hinged key-rest, substantially as described.

5. In a piano, the combination, with the pedal-rod, of a pivoted key-rest and a relatively-movable rod loosely jointed to said key-rest and provided with an arm pivotally connected to the said pedal-rod, substantially as and for the purposes described.

6. In a piano, the combination, with a sliding stop, of a pedal-rod provided with projections engaging with said stop, and a movable key-rest operated by said pedal-rod, substantially as and for the purposes described.

In witness whereof I have hereunto set my hand.

EDWARD N. CUMMINGS.
